UNITED STATES PATENT OFFICE.

JAMES L. BLACK, OF ALEXANDRIA, MINNESOTA.

INTERNAL-COMBUSTION ENGINE.

1,308,326.

Specification of Letters Patent. Patented July 1, 1919.

Application filed January 23, 1918. Serial No. 213,408.

To all whom it may concern:

Be it known that I, JAMES L. BLACK, a citizen of the United States, residing at Alexandria, in the county of Douglas and 5 State of Minnesota, have invented certain new and useful Improvements in Internal-Combustion Engines, of which the following is a specification.

This invention has relation to internal 10 combustion engines, and has for an object to provide an engine of this type embodying a cylinder open at each end and having mounted therein a pair of pistons movable toward and away from each other whereby 15 the explosion may take place between the adjacent ends of the pistons to drive the same in opposite directions.

Another object of the invention is to provide an internal combustion engine embodying one or more cylinders, each open at each 20 end and having mounted in each a pair of pistons adapted for movement toward and away from each other, and means for operatively connecting the opposed pistons of 25 each cylinder so as to insure movement thereof in unison, and whereby the power of the engine may be increased without the necessity of increasing the number of cylinders, and whereby an efficient long stroke 30 and small piston diameter engine may be obtained.

Another object of the invention is to provide an internal combustion engine embodying a plurality of cylinders having combustion 35 chambers formed at their intermediate portions, a pair of pistons movable in each cylinder toward and away from each other with means for communicating motion between the opposed pistons, and valves located within the combustion chambers to 40 control inlet and exhaust ports, each valve having its stem directed toward the crank shaft at the side of the engine upon which the valve is located with cam means for 45 opening the valves at the proper interval to permit operation of the engine in accordance with the four cycle principle.

A still further object of the invention is 50 to provide means in an internal combustion engine of the character above set forth mounting the exhaust valve in packing glands integrally formed with the water jacket and appurtenant parts, and remov-

able cages for the intake valves to support the same whereby the valve may be readily 55 assembled in the engine and whereby the number of parts is materially reduced.

A still further object of the invention is to provide a valve operating mechanism in the nature of a cam of a specific type adapted 60 for coaction with a revolute valve stem, mounted also for reciprocatory movement to open and close the valve, whereby the valves may have imparted thereto a rotary movement through a partial revolution at each 65 engagement of the cam with the valve stem or when acting to move the valve to closed position so as to present a new portion of the valve for engagement with a different portion of the valve seat each time to insure 70 uniformity in the wear of the valve, and thereby improve the compression of the engine.

A still further object of the invention is to provide an internal combustion engine of 75 the type above set forth, designed particularly for use in motor vehicles, embodying means for communicating motion between the crank shaft, and a clutch mechanism including a friction wheel for each crank shaft, 80 and a third friction wheel movable therebetween mounted in a specific manner whereby the third friction wheel may be brought into engagement with the pair of friction wheels to receive motion therefrom or disengaged 85 at will.

In addition to the foregoing my invention comprehends improvements in the details of construction and arrangement of the correlative parts to be hereinafter more fully 90 described and particularly set forth in the appended claims.

In the accompanying drawings in which similar and corresponding parts are designated by the same characters of reference 95 throughout the several views in which they appear:—

Figure 1, is a view in front elevation, with parts broken away of an internal combustion engine constructed in accordance 100 with my invention, illustrating particularly the clutch mechanism.

Fig. 2, is a horizontal section taken on the line 2—2 of the preceding figure.

Fig. 3, is a longitudinal vertical section 105 taken on the line 3—3 of Fig. 2, and

Fig. 4, is a detail view of one of the cams and valve operating mechanism constructed in accordance with my invention.

With reference to the drawings, 10 indicates the engine cylinders, of which four are provided in the present instance, located in parallelism and cast in pairs with water jackets 11 formed adjacent their intermediate portions. Each cylinder is open at each 10 end, and is enlarged or grooved circumferentially at its intermediate portion as indicated at 12. Each cylinder is furthermore formed adjacent its intermediate portion with a lateral upwardly extending extension 13 designed to form a combustion chamber in 15 communication with the annular groove 12 the combustion chamber of one cylinder being separate and independent of that of the other cylinders. The water jacket 11 is enlarged to inclose the combustion chamber 13. In one end wall of the combustion chamber is formed an opening 14 having a valve seat thereabout, and said opening 14 is in communication with a port 15 which extends 20 through the water jacket and is flanged exteriorly for connection to an exhaust manifold (not shown). The shell of the jacket near the exhaust port 15 is formed with an apertured enlargement 16 defining a packing 25 gland or guide for a valve stem which is disposed parallel to and above its associated cylinder. A conical valve 18 of conventional type is mounted upon the inner end of each valve stem 17 for engagement upon the valve 30 seat. Each valve chamber 13 is furthermore formed through the opposite end wall with a relatively large opening 19 designed to receive the reduced end 20 of a valve cage indicated generally at 21, one valve cage being 35 provided for each cylinder. Each valve cage 21 is preferably cylindrical in configuration, and is tapered at 22 at its end opposite that end provided with the reduced extension 20. Each valve cage is furthermore formed with 40 an arcuate passage or intake port 23 designed for communication at one end with a flanged coupling member 24 formed integrally with the shell of the water jacket, and its opposite end opening into the combustion chamber and forming a valve seat 45. Each valve cage 21 is formed with a central tubular member 26 forming a packing gland or guide for the valve stem 27 which extends in parallelism to and above its associated cylinder in alinement with its associated valve stem 17 and extending oppositely thereto. The water jacket is formed with an internally threaded tubular extension 28 around each cavity in which the 50 valve cage 21 is received, and a threaded plug 29 is engaged in said threaded extension against the tapered portion 22 of the valve cage to retain the same in place. A gasket 30 may be interposed between the 55 meeting faces of said plug and valve cage to

form a tight joint. A pair of crank casings 31 are provided, secured across the outer ends of the cylinders in any suitable fashion to support in each a transversely extending crank shaft 32 having offsets for connection 70 to connecting rods 33 which are connected at their opposite ends to pistons 34, of which a pair are located in each cylinder for movement toward and away from each other. Mounted upon each crank shaft 32 at adjacent ends is a pinion 33 forming part of timing gears, the other members of which are indicated at 33 and constituted by pinions mounted upon cam shafts 35 which extend through the crank casing in proximity 80 to the outer ends of the valve stems 27 and 17. The outer end of each valve stem 17 and 27 is threaded and inserted in a tubular plunger rod 36 which is guided within the tubular extension 37 of the crank case extending inwardly. Jam nuts 38 are applied to the valve stem for engagement against the outer ends of the plunger rod 36 so as to vary the length of the structure thus defined. Each plunger is provided with an integrally formed head 39 having a race-way formed in its inner face to receive spherical bearing members 40 which also operate in a race-way formed in a disk 41 encircling the plunger rod. A coil spring 42 is embraced about each plunger rod 36 to bear at one end against the inner surface of the crank case and at its opposite end against the disk member 41. Each cam shaft is provided with cams indicated at 44, and corresponding in number to the number of cylinders. Each cam is beveled on one side face as indicated at 43 so as to present a substantially cuneiform appearance in edge view as shown in Fig. 4. The narrowest portion of the cam should be located opposite the nose of the cam and of a width slightly less than the radius of the discous enlargement 39, the larger end of the cam corresponding in width to the diameter of 100 said enlargement. Each cam is located with relation to the discous enlargement 39 so that the narrow portion of the cam when engaging the discous enlargement 39 will bear upon the same entirely to one side of the axis of 105 said discous enlargement, or the axis of the associated valve rod, while in another position of the cam the broadest portion may engage the entire face of the discous enlargement. The crank shafts are provided upon adjacent ends with sprocket wheels 45, said sprocket wheels being located exteriorly of the casing, and connected by means of a silent chain 46. The sprockets 45 and chain 46 are inclosed within a casing 47, open at 110 one side and secured to the casing 31 of the engine, a cover plate 48 being subsequently applied to the open end of said casing 47 whereby said casing may be filled with oil or other lubricant. The opposite end of the 115

120

125

130

crank shafts 32 are extended exteriorly of their casings and provided with friction disks having suitable frictional material applied to their peripheries for engagement with a friction disk 50 movable therebetween and similarly provided with friction material. The disks 49 and 50 are adapted for peripheral engagement and for disposition in the same plane, and the friction wheel 50 is mounted upon a shaft 51 connected, by means of a universal joint 52 to the shaft of the transmission mechanism (not shown). The universal joint 52 permits the transmission of power between the transmission and the shaft 51 and at the same time permits vertical movement of said shaft. The shaft 51 is supported in a bearing 53 constructed to reduce friction therebetween through the provision of roller or ball bearings, and said bearing member 53 is provided with oppositely extending horizontal trunnions 54 which are seated with enlargements 55 therefor, formed in a split supporting member 56. The supporting member 56 is secured to the lower end of a vertically movable cylindrical rod 57 slidably mounted in a bracket 58 mounted upon the end of the frame or any suitable support. The upper end of the member 57 is embraced by means of a flanged collar 59, and is reduced and threaded above the flanged collar to receive a pair of nuts 60. A coil spring 61 is then embraced about said member 57 and interposed between the upper end of the bearing member of the bracket 58 and the under side of the flanged collar 59 whereby to urge said member 57 and also the shaft in an upward direction to bring the friction wheel 50 into engagement with its coacting members 49. A bell crank 62 may be provided to depress the member 57 by engagement of one arm with the upper end of said member 57 whereby to move, against the tension of the spring 61 the wheel 50 from engagement with the coacting wheel 49 thereby discontinuing the transmission of power therebetween.

The offsets of the crank shaft are so arranged preferably, as to dispose the pistons of the intermediate cylinders in positions in proximity to each other while the pistons of the remote cylinders are located at opposite ends of their cylinders substantially as shown in Fig. 2. It will be obvious however, that this arrangement may be varied at will without departing from the spirit of the invention. The cams are furthermore arranged relative to the positions of the pistons at different times so that while an explosion is taking place within the explosion chamber of one pair of cylinders, the remaining pistons will be undergoing the other phases of the operation of a four-cycle engine, viz: compression, intake and exhaustion. The explosion in any event, is de-

signed to take place when the pistons of one cylinder are in mutual proximity so that the force of the explosion may drive them in opposite directions, and the full value of the expansive force of the gas is utilized. In 70 this manner an engine embodying this principle of double action may operate with a long stroke, and relatively small piston diameter. The valves are designed to be opened and closed at proper periods by the 75 action of the cams 42 substantially in the manner of the conventional type of internal combustion engines to supply charges to the combustion chamber and to permit the exhaustion therefrom of burnt gases. The 80 cam shafts 35 are operated by the transmission of power from the crank shafts through the gears 33 and 34 which should be properly proportioned. With regard to the operation of the cams it is to be noted that 85 when considering any cam when the same is moving so as to permit the valve operated thereby to return to closed position, the thinnest portion of the cam will engage the disk member 39 adjacent the periphery 90 thereof thereby applying a slight rotary motion thereto with the result that the valve stem and consequently the valve is rotated through a partial revolution and each time the valve is permitted to engage the valve 95 seat at a different point thereof. In this manner the wear upon the valve is uniform and the compression of the engine maintained through a longer period than would be the case if the valves were opened and 100 closed without rotating the same. Attention is called to the valve cage 21 of the intake port forming a mounting for the valve and at the same time permitting the disassembly of the said valves and valve stems. 105 It will be noted that if the plugs 29 are withdrawn and the valve cages 21 are removed from their cavities the exhaust valves 18 may be readily withdrawn through the cavities occupied by said valve cages, by disconnecting the plungers from said valve stems. From the foregoing it will be obvious that I have provided an internal combustion engine of a new and novel construction in which the crank shaft may be provided with 115 relatively large throws thereby economizing in the use of fuel, the maximum amount of expansion of the gases being utilized. I furthermore provide a novel combination of this type of internal combustion engine 120 with a clutch mechanism of the friction type in the form of a transmission and also clutch mechanism which possesses the advantage that there is very little wear upon the friction element. The form of clutch 125 mechanism herein described is furthermore superior to the cone or disk clutch in that the application of power takes place more gradually, the friction wheels 50 rotating freely upon engagement with the wheels 49 130

until firm frictional engagement therebetween is established. Other uses and advantages will readily occur to those familiar with the art to which this invention appertains.

While I have illustrated and described my invention with some degree of particularity, I realize that in practice various alterations thereof may be made, and I therefore desire to reserve the right and privilege of changing the form of the details of construction, or otherwise altering the arrangement of the correlative parts without departing from the spirit of the invention or the scope of the appended claims.

Having thus described my invention, what I claim as new and desire to secure by Letters Patent is:—

1. In an internal combustion engine, the combination with a horizontal cylinder having an upstanding combustion chamber at its mid-length, the end walls of said chamber being pierced with openings, alined pistons within said cylinder, crank cases at its extremities, and shafts therein whose cranks are connected with said pistons to cause them to move oppositely and simultaneously; of a water jacket surrounding the mid-length of the cylinder and the combustion chamber, an exhaust port communicating with one of said openings, a valve therefor, a cam in one crank case for actuating this valve, a cage whose inner end fits the opening in the other wall of the combustion chamber and whose body contains an intake port having a valve seat in its inner end, a valve therefor, and a cam in the other crank case for actuating this valve.

2. In an internal combustion engine, the combination with a horizontal cylinder having an upstanding combustion chamber at its mid-length, the end walls of said chamber being pierced with openings, alined pistons

within said cylinder, crank cases at its extremities, and shafts therein whose cranks are connected with said pistons to cause them to move oppositely and simultaneously; of a water jacket surrounding the combustion chamber and cylinder at its mid-length and cored with an opening constituting the exhaust port and having a valve seat at its inner end, a valve for this seat, a cam in one crank case for actuating said valve, a guide formed within the shell of the water jacket for the seat of the exhaust valve, a cage removably closing the opening in the other wall of the combustion chamber and provided with an opening constituting the intake port and having a valve seat at its inner end, the cage having a guide through its body, a valve for said seat, the stem thereof extending through said guide, and a cam in the other crank case for actuating this valve.

3. An internal combustion engine consisting of a horizontal cylinder of double length enlarged annularly between its ends and cast with an upstanding combustion chamber communicating with the enlargement, a waterjacket whose shell incloses the annular enlargement and the combustion chamber, the end walls of the latter having intake and exhaust ports, valves for the same, valve stems extending parallel with and above the cylinders, crank casings at the outer ends of the latter, crank shafts therein, cams connected with the crank shafts and actuating the valve stem and pistons driven by the cranks and mounted in said cylinder.

In testimony whereof I affix my signature in presence of a witness.

JAMES L. BLACK.

Witness:

M. E. JONES.
